PAVEMENT

Wallace C. Fischer, Chicago, Ill.

Application July 6, 1931, Serial No. 548,782

1 Claim. (Cl. 94—18)

This invention relates to street pavings comprising a layer of rigid material divided and spaced at intervals to divide the layer into sections, and expansion joint strips inserted in these 5 intervening spaces to provide for contraction and expansion for the rigid material.

Heretofore expansion strips have been provided with a longitudinal medial tongue and groove co-extensive with the length of the strips, and with 10 the tongue and groove deformed from the strips. Strips of this construction are difficult to stack and handle, and frequently the tongue and groove portion is injured.

It is the purpose of the present invention to 15 construct as separate articles of manufacture a base strip of conventional form provided with one or more recesses, and tongue and groove pieces which may at the time be inserted in the recesses. Or the base sheet may be used without the insertion 20 of any tongue and groove pieces, or the recesses of the base strip may be refilled with the pieces (or similar pieces) cut therefrom in providing the recesses. Accordingly there is produced a novel and improved expansion joint strip 25 which may be selectively used for various expansion joint forms.

For a better understanding of the invention reference may be had to the accompanying drawing, in which:

30 Figure 1 is a perspective view of an expansion joint embodying the present invention;

Figure 2 is a cross sectional view of a paving structure in which the expansion joint strip is inserted; and

35 Figure 3 is another cross-sectional view of a paving structure in which the expansion joint strip is inserted.

Referring to the drawing, numeral 2 designates 40 a strip of moldable material, such as rubber or the like, provided with one or more medial re-

cesses 3, which may be molded therein or cut out after the strip is formed. These recesses are preferably elongated longitudinally and any desired number of them may be formed in the strip.

For insertion within the recesses of the strip elongated tongue and groove sections 4, separably formed, are provided. They may be molded from the same material as is used in making strips 2 or they may be of any other material. The sides 10 of the tongue and groove sections may advantageously be provided with flanges or ribs 5 to engage with corresponding recesses 6 in the expansion strips in order to engage and better secure the sections to the strips. 15

With the tongue and groove sections fitted in the recessed strips, the complete expansion unit is adapted to be inserted between concrete slabs 7 and 8 to separate same and allow for contraction and expansion. 20

Perforations 9 are provided in the tongue and groove sections to accommodate transverse rods which are commonly embedded to engage the ends of the concrete sections. 25

While I have shown one preferred embodiment 30 to illustrate the invention, it is not to be understood that there is any limitation as to details of construction as these may be changed without departing from the spirit of the invention.

I claim:

An expansion joint strip comprising a base sheet provided with one or more elongated recesses, and filling sections for said recesses, said filling sections projecting outwardly of the plane 35 of the strip and being separate from the strip and tongue and groove joints formed between said base sheet and the filling sections, said filling sections being of substantially the same structure and thickness as the base sheet.

WALLACE C. FISCHER. 40
